UNITED STATES PATENT OFFICE.

JOHN WILLIAM TAGERT, OF STAMPS, ARKANSAS.

CAR-BRAKE.

1,069,907.

Specification of Letters Patent. Patented Aug. 12, 1913.

Application filed August 24, 1912. Serial No. 716,934.

To all whom it may concern:

Be it known that I, JOHN WILLIAM TAGERT, a citizen of the United States, residing at Stamps, in the county of Lafayette and 5 State of Arkansas, have invented certain new and useful Improvements in Car-Brakes, of which the following is a specification, reference being had to the accompanying drawings.

10 This invention relates to new and useful improvements in adjustable hand operating brake mechanism for railway cars, the object of the invention being to provide a hand brake which can be quickly and easily operated when disposed either in a vertical or 15 horizontal position.

Another object of the invention is to provide improved means for locking the brakes after they have been applied, said means being adapted to be easily released so as to 20 free the brakes.

A further object of the invention is to provide a brake mechanism of the above character which will possess advantages in 25 points of efficiency and durability, is inexpensive to manufacture and at the same time is simple in construction and operation.

With the above and other objects in view, the invention consists in the novel features 30 of construction and the combination and arrangement of parts hereinafter more fully described, pointed out in the claims, and shown in the accompanying drawings in which—

35 Figure 1 is an elevation. Fig. 2 is a vertical sectional view. Fig. 3 is a sectional view on the line 3—3 of Fig. 2. Fig. 4 is a vertical sectional view illustrating a slightly modified form.

40 Referring more particularly to the drawings, 1 indicates the car upon the end of which is mounted the supporting bracket 2, extending upwardly from the base of the bracket and formed integral therewith are

45 the two spaced ears 3 each of which is provided with an opening 4 adapted to receive the tubular member 5 in which the lower end of the rod 6 is mounted. Rigidly mounted upon one side of the supporting

50 bracket 2 is a curved rack bar 7 upon which is adjustably mounted the bifurcated extension 8 which is formed integral with one side of the collar 9, said collar being suitably secured to the lower end of the tubular body 55 member 10.

Slidably mounted in the eye bolt 11 is the

rod 12, the lower end of which is provided with a tapered engaging member 13 adapted to engage the notches 14 in the bar 7 to hold the body member 10 in various adjusted 60 positions. The lower end of the rod 12 is held securely in engagement with the notches 14 by means of the coil spring 15 which is mounted upon the rod and arranged between the eye bolt 11 and the engaging 65 member 13. The member 13 at the lower end of the rod 11 is adapted to be removed from the notches 14 by means of the pivoted handle member 16. Mounted upon the upper end of the body member 10 is a U shaped 70 supporting member 17 which is provided with upwardly extending spaced arms 18 in which is mounted the shaft 19 having a beveled gear 20 mounted thereon and arranged between the arms. Mounted upon 75 the upper end of the rod 6, which extends upwardly through the body member 10, is a second gear 21 adapted to mesh with the gear 20 so that when the hand wheel 22 which is mounted upon the outer end of the 80 shaft, is turned the rod 6 will be rotated to wind up the brake chain 23 and set the brakes.

Mounted within the flanges 24 upon the outer face of the arms 18 is a ratchet 25 85 which is adapted to be engaged by a similar ratchet 26 mounted upon the shaft 19 to hold the brakes in a locked position until it is desired to release the same. In winding up the brake chain, the hand wheel 22 is 90 pulled toward the operator to disengage the ratchets 25 and 26 so as to leave the wheel free to be turned and rotate the shaft 19 and the gear 21 which in turn will rotate the rod 6 through the gear 20 and wind up the brake 95 chain 23. After the chain 23 has been tightened so as to set the brake, the hand wheel 22 is pushed outwardly to engage the ratchets 25 and 26 and lock the brake in its operative position.

100 From the above description taken in connection with the accompanying drawings it will be readily apparent that my improved brake operating mechanism will be especially valuable upon flat cars or other similar cars which are used to transport logs, telephone poles, etc., as the device may be adjusted and arranged in a horizontal plane so as to be entirely out of the way in case the logs or telephone poles should extend beyond the ends of the car.

105 In Fig. 4, I have illustrated a slightly

modified form of the invention wherein the hand wheel 22 is arranged directly at the upper end of the body member 10. In this form of my invention, the hand wheel 22 is mounted directly upon the upper end of the rod 6, and the supporting member at the upper end of the body member 10 is provided upon each side thereof with the flanges 26 in which is mounted the ratchet 27 adapted to engage with a similar ratchet 28 secured to the central portion of the hand wheel 22. In operating this form of mechanism, the hand wheel 22 is to be rotated in one direction to wind up the brake chain 23, the ratchets 27 and 28 preventing backward movement of the wheel. After the brake chain 23 has been tightly wound, the ratchets 27 and 28 will engage each other to hold the wheel 22 against rotary movement and when it is desired to release the chain 23, the wheel 22 is pulled upwardly to disengage the ratchets 27 and 28 so as to allow the wheel 22 and the rod 6 to rotate and unwind the chain.

25 The rod 6 is provided adjacent its upper end with a transverse opening 29 in which is arranged a pin 30, the ends of said pin being arranged in the space between the top end of the body member 10 and the ratchet 27 to prevent the body member 10 from sliding upwardly upon the rod 6.

30 From the above description taken in connection with the accompanying drawings, it will be readily apparent that I have provided a simple and durable brake operating mechanism of the above character which can be quickly and easily operated when arranged in a vertical or horizontal plane and which at the same time can be manufactured and applied to various varieties of cars at 35 extremely low cost.

40 While I have shown and described the preferred form of my invention, it will be obvious that various changes in the details of construction and in the proportions may be resorted to for successfully carrying my invention into practice without sacrificing any of the novel features of construction or departing from the scope thereof.

45 What I claim is:—

50 1. In a device of the character described, the combination of a supporting bracket, a rod having its lower end pivotally mounted upon the base of said bracket, a curved rack bar upon one side of said bracket, a tubular body member adjustably mounted upon said rod and inclosing the same, and means carried by said body member and adapted to engage the rack bar to hold the body member in various angular positions.

55 2. In a device of the character described, the combination of a supporting bracket, a rod having its lower end pivotally mounted upon the base of said bracket, a curved rack bar upon one side of the bracket, a tubular

body member adjustably mounted upon the rack bar and inclosing said rod, a U-shaped supporting member mounted upon the upper end of the body member, having upwardly extending spaced arms, a shaft mounted in said arms, a gear on said shaft and arranged between the arms, a gear upon the upper end of said rod and meshing with the first gear and means for operating said gears to rotate said rod.

60 3. In a device of the character described, the combination of a supporting bracket, a rod having its lower end pivotally mounted upon the base of said bracket, a curved rack bar upon one side of said bracket, a tubular body member mounted upon said rod, a collar secured to the lower end of the body, a bifurcated extension formed on said collar and adjustably mounted upon said rack bar, and means mounted upon the upper end of the body for rotating said rod.

65 4. In a device of the character described, the combination of a supporting bracket, a rod having its lower end pivotally mounted upon the base of said bracket, a curved rack bar, upon one side of said bracket, a tubular body member adjustably mounted on the rack bar and inclosing said rod, a U-shaped supporting member mounted upon the upper end of the body member, having upwardly extending spaced arms, a shaft mounted in said arms, a gear on said shaft and arranged between the arms, a gear upon the upper end of said rod and meshing with the first gear, a hand wheel mounted upon the outer end of the shaft, a ratchet mounted upon one of said arms and a second ratchet mounted upon the hand wheel and adapted to mesh with the first ratchet to prevent backward movement of the hand wheel.

70 5. In a device of the character described, the combination of a supporting bracket, spaced ears formed integral with the base of said bracket and extending upwardly therefrom, said ears being provided with openings, a tubular member mounted in said openings, a rod having its lower end mounted in said tubular member, a curved rack bar upon one side of said bracket, a tubular body member adjustably mounted upon said rack bar and inclosing said rod, a U-shaped supporting member mounted upon the upper end of the body member, having upwardly extending spaced arms, a shaft mounted in said arms, a gear on said shaft and arranged between said arms, a gear upon the upper end of said rod meshing with the first gear, and means for operating said gears to rotate the rod.

75 6. In a device of the character described, the combination of a supporting bracket, a rod having its lower end pivotally mounted upon the base of said bracket, a curved rack bar upon one side of said bracket, a tubular body member adjustably mounted upon said

rod and inclosing the same, means carried by said body member and adapted to engage the rack bar to hold the body member in various angular positions, and means 5 mounted upon the upper end of the body member for rotating the said rod.

7. In a device of the character described, the combination of a supporting bracket, a rod having its lower end pivotally mounted 10 upon the base of said bracket, a curved bar upon one side of the bracket, a tubular body member adjustably mounted upon said rod and inclosing the same, a U-shaped supporting member mounted upon the upper 15 end of the body member, a shaft mounted in said supporting member and means mounted on said shaft for rotating said rod.

8. In a device of the character described, the combination of a supporting bracket, a 20 rod having its lower end pivotally mounted upon the base of said bracket, a curved rack bar upon one side of the bracket, a tubular member adjustably mounted upon said rod

and inclosing the same, means carried by said body member and adapted to engage 25 the rack bar to hold the body member in various angular positions, a U-shaped supporting member mounted upon the upper end of the body member, a shaft mounted in said supporting member and means mounted 30 upon said shaft for rotating said rod.

9. In a device of the character described, the combination of a supporting bracket, spaced ears formed integral with the base of said bracket, and provided with aligned 35 openings, a tubular member mounted in said openings, a rod having its lower end mounted within said tubular member, means for adjusting said rod to various angular positions and means for rotating the same. 40

In testimony whereof I hereunto affix my signature in the presence of two witnesses.

JOHN WILLIAM TAGERT.
